CLAIM

The ornamental design for a screwdriver, as shown and described.

DESCRIPTION

FIG. 1 is a perspective view of a screwdriver showing our new design;

FIG. 2 is a right side elevational view thereof;

FIG. 3 is a front view thereof;

FIG. 4 is a top view thereof;

FIG. 5 is a left side view thereof;

FIG. 6 is a rear view thereof; and,

FIG. 7 is a bottom view thereof.

Broken lines illustrate features of the screwdriver that form no part of the claimed design.

1 Claim, 3 Drawing Sheets(56)
